(74) Attorney, Agent, or Firm — Renner, Otto, Boisselle & Sklar, LLP

(57) **CLAIM**

The ornamental design for pliers, as shown and described.

DESCRIPTION

FIG. 1 is a front elevation view of pliers showing my new design;

FIG. 2 is a rear elevation view thereof;

FIG. 3 is a top plan view thereof;

FIG. 4 is a bottom plan view thereof;

FIG. 5 is a left side elevation view thereof; and,

FIG. 6 is a right side elevation view thereof.

The broken line showing is for the purpose of illustrating unclaimed portions of the article and forms no part of the claimed design.

1 Claim, 4 Drawing Sheets
